UNITED STATES PATENT OFFICE.

ALBERT A. BRUDER, OF HOLLY, MICHIGAN.

FURNACE.

Application filed December 1, 1922. Serial No. 604,294.

To all whom it may concern:

Be it known that I, ALBERT A. BRUDER, a citizen of the United States of America, residing at Holly, in the county of Oakland and State of Michigan, have invented certain new and useful Improvements in Furnaces, of which the following is a specification, reference being had therein to the accompanying drawings.

10 In my United States Patent No. 1,419,011, granted June 6, 1922, there is disclosed a furnace including a combustion chamber, flues adapted to cause products of combustion to travel from the top of the combustion chamber to a point below the fire therein and other flues communicating with the combustion chamber at the fire therein for conducting solid units upwardly above the combustion chamber and independent of the 20 first mentioned flues. This constructive arrangement of flues for producing drafts in the furnace has been found satisfactory, and the present invention includes the same principle with certain refinements by which the 25 furnace is rendered more efficient, especially for various heating systems and various kinds of fuel. For instance, I find that the lowest grades of solid fuel may be burned in my improved furnace. Even ashes and 30 various kinds of refuse matter can be burned because the flue arrangement insures proper drafts for the combustion of such matter, and it is in this connection that the gaseous matter is also burned reducing to a minimum the waste of combustible products to 35 the atmosphere.

With this résumé of my prior patent the present invention may be characterized in the following particulars.

40 First, the furnace as now constructed may be used for a hot air, hot water or steam heating system, or constructed to supply hot water in conjunction with hot air. This latter arrangement is advantageous for residence use and eliminates the usual hot water boiler or tank.

Second, the construction of the furnace is such that units may be added thereto to increase the output of the furnace for either 45 water, steam or air heating system.

Third, the furnace is provided with a novel arrangement of dampers adapted for manual adjustment or automatic adjustment in conjunction with an ash pit door of the 50 furnace, the latter adjustment precluding

any possibility of ashes being blown from the furnace or obnoxious gases escaping therefrom into a cellar or room in which the furnace may be located.

Fourth, the furnace is provided with fire 60 sight openings or twyer members which permit of the condition of the fire within the furnace being observed without moving any part of the furnace, and these sight openings afford a degree of light adjacent the furnace which may provide sufficient illumination in a dark cellar for a furnace attendant to fire the furnace without any additional light.

55 Fifth, the furnace includes an arrangement of water receptacles to insure a supply of hot water and a natural amount of moisture in the air about the furnace. The receptacle which supplies the hot water serves as a water jacket about that part of the combustion chamber subjected to an intense heat and this water jacket precludes fracture or buckling of chamber and flue walls subjected to the fire within the furnaces.

65 The above are a few of the features of my 80 invention obtained by the constructive arrangement of parts to be hereinafter described and then claimed, and reference will now be had to the drawings wherein—

70 Figure 1 is a vertical longitudinal sectional view of a furnace in accordance with my invention;

75 Fig. 2 is a vertical cross sectional view of the furnace as constructed from interchangeable units adapted to increase the capacity 90 of the furnace;

80 Fig. 3 is a vertical cross sectional view taken on the line III—III of Fig. 1;

85 Fig. 4 is a perspective view of detached dampers and the operating mechanism of 95 such dampers;

Fig. 5 is a detail sectional view of a portion of the damper operating mechanism;

Fig. 6 is a plan of the greater part of the furnace, partly broken away and partly in 100 horizontal section, and

Fig. 7 is a front elevation of a portion of the furnace.

In the drawings, the reference numeral 1 denotes a substantially rectangular base 105 piece providing an ash pit or chamber 2 which has its rear wall provided with an air inlet opening 3, and the front end of the base piece is open to communicate with an opening 4 in a casing wall 5 which may be 110

considered as an outer front wall of the furnace structure. The opening 4 is normally closed by a hinged door 6 having its hinged pintle 7 extending upwardly in front of the wall 5 and journaled in a bearing 8 carried by said wall. The purpose of this elongated pintle will hereinafter appear when considering the damper operating mechanism.

The top of the base piece or ash pit has a 10 large opening and a seat 9 for a conventional form of grate 10, and suitably mounted on the base piece 1, over the grate 10 is a combustion chamber 11 having inner side walls 12, outer side walls 13 of less height than the 15 walls 12, a rear wall 14, a front wall 15, and diverging or angularly disposed flue connections 16, said flue connections, the walls 12, 14 and 15 cooperating with horizontal walls 17 in forming a trough 18 and water 20 compartments 19. The water compartments 19 are triangular in cross section, as best shown in Fig. 3 and extend along the sides of the combustion chamber between said chamber and the flue connections 16. The 25 water compartments also correspond in length to the combustion chamber and afford jackets on the lower sides of the combustion chamber so that water placed in said jackets or circulated therethrough may assist in 30 cooling the walls of the combustion chamber and flue connections where said flue connections open into the combustion chamber.

In the horizontal walls 17 are detachable 35 screw plugs 20 which permit of the trough 18 being placed in communication with the water compartments or jackets 19 and such communication is established when the furnace is to be used other than for water heating purposes. The trough 18 has a rear portion 21 outstanding from the wall 14 and a front portion 22 outstanding from the wall 15, thus providing a trough about the sides of the combustion chamber adapted to contain water which will be heated by conduction 40 from the walls of the combustion chamber and afford sufficient moisture so that air about the furnace will be moisture laden and not oppressively dry.

At one side of the trough and at the rear 50 portion 21 thereof is an extension 23 protruding through an opening 24 in a casing 25 inclosing the furnace, said casing being of any suitable design that may rest on the bottom ring 26, be secured to the front wall 55 5, as at 27, and afford suitable air inlet and outlet openings. These openings as well as hot air flues have not been shown on account of being conventional in many forms 60 of hot air furnaces. The trough extension 23 can be readily supplied with water controlled by an ordinary feed water regulator or float controlled valve so that as the water within the trough is absorbed by the air the trough may be replenished. It is 65 also obvious that with the trough exten-

sion 23 extending out of the casing 25 that the trough may be manually filled from time to time.

Connected to the wall 14, at the rear ends of the water compartments or jackets 19, 70 are branch water inlet pipes 28 communicating with a main water supply pipe 29. The water admitted to the bottom of each water jacket is removed from the top thereof by branch outlet pipes 30 connected to the wall 75 15 and a main hot water outlet pipe 31. The pipe 29 is located outside of the casing 25 and may be equipped with a valve to control the supply of water to the water jackets and consequently the outlet of water to the pipe 80 31, this pipe extending upwardly in the casing 25 and out of said casing to supply hot water for any desired purpose. It may be connected to radiators, water outlet fixtures or to a storage tank, but insomuch that 85 the water jackets serve functionally as a water boiler such a tank may be eliminated.

Mounted on or suitably secured to the upper edges of the walls 12 and 14 of the combustion chamber is a magazine chamber composed of side walls 32 and 33, an arched upper wall 34, and a rear wall 35. The walls 32, 33 and 34 join the front wall 5 and the combustion chamber 11 has its wall 15 provided with a forwardly extending channel shaped portion 35 meeting the wall 5 at an opening 36 in said walls, said opening being normally closed by a hinged door 37. The channel portion 35 cooperates with the magazine chamber in affording a fuel entrance to the combustion chamber, consequently the magazine chamber may have fuel stored therein for consumption as fast as fuel is consumed in the combustion chamber 11 above the grate 10. In practice a live 100 bed of coals is maintained on the grate 10, burning at the lower ends of the flue connections 16 and under the coal or fuel within the upper part of the combustion chamber and the magazine. 105

The rear wall 35 of the magazine has a large opening 37 and communicating with said opening is a down flue 38 having its lower end communicating with the opening 3 in the rear wall of the ash pit or base 115 piece 1.

Extending into the large opening 37 of the magazine is the rear downwardly turned or mitered end 39 of a cold air draft flue 40 extending forwardly through the magazine to an opening 41 in the front wall 5, said opening being partially closed by a hinged flap door 42 provided with air inlet openings 43. The cross sectional shape and area of the cold air draft flue 40 is less than that of the opening 37 so that a draft in the down flue 38 causes an entraining action at the opening 37 to pull smoke, dust and gases from the upper part of the combustion chamber and magazine and deliver the 120 125 130 135 140 145 150 155 160 165 170 175 180 185 190 195 198 200

gaseous matter to the ash pit below the grate 10, through which grate the gaseous matter encounters the live bed of coals and is either consumed or finds exit by the flue 5 connections 16.

The upper end of the down flue 38 has a T connection 44 adapted to have its vertical portion communicate with the atmosphere through the lateral portion of said T connection which lateral portion constantly communicates with the atmosphere. The forward end of the T connection 44 communicates with the middle portion of an arched flue 45 extending transversely over the magazine and said arched flue has a divisional wall 46 in front of the opening 47 which establishes communication between the flue 45 and the T connection 44. The ends of the flue 45 are connected to the upper ends of up-flues 48 having the lower ends thereof mounted on the walls 13 and the upper ends of the flue connections 16, thus establishing communication between the atmosphere and the bed of fire in the combustion chamber. An updraft is produced in each of the flues 48 and should a slow burning or damped fire at the lower end of either flue connection 16 retard the updraft in one of the flues 48, the other flue, by reason of the divisional wall or baffle 46, will cause somewhat of an entraining action in the slow draft flue and thus cause the slow burning fire at the lower end of such flue to become more intense and eventually equalize the draft of both flues. The divisional wall or baffle 46 therefore precludes either of the flues 48 remaining dormant for any great period of time, and insures an equal draft in each flue.

In the vertical portion of the T connection 44 is an annular damper seat 49 for an inverted cup shaped damper 50 adapted to shut off the direct atmospheric communication between the T connection 44, the upper end of the down flue 38 and the magazine. The damper 50 has a stem 51 slidable in a spider bearing 52 in the vertical portion of the T connection 44, and operatively connected to the lower end of the stem 51 is the forked end 52a of a pivoted actuating bar 53 extending through the opening 37 and forwardly in the top of the magazine where the forward end of said bar is supported, as at 54 from the arched top wall 34 of the magazine.

Normally resting on top of the cold air draft flue 40 is a short arm 55 and a long arm 56 either of which may be actuated to impinge against the bar 53 and cause said bar to raise the damper 50 and establish communication between the atmosphere, the down flue 38 and the magazine. The long arm 56 is mounted on a longitudinally disposed rock shaft 57 supported in a bracket or bearing 58 carried by the magazine wall

33 and the forward end of said rock shaft is journaled in the front wall 5 with the outer end of said shaft provided with a crank 58. Normally engaging the crank 58 is a bell crank 59 supported from the wall 5, said bell crank being attached to a rod or flexible member 60 adapted to be actuated from a point remote from the furnace. The damper 50 closes by gravity, but may be opened from a hall or room into which the rod or flexible member 60 extends.

The short arm 55 has a bifurcated end 61 loosely mounted on a rock shaft 62 journaled in the front wall 5 and the magazine wall 35. On the forward outer end of the rock shaft 62 is a crank 63 connected, as at 64, to a crank 65 on the upper end of the ash door pintle 7, previously referred to.

On the rock shaft 62, in the magazine, is a cam member 66 and a crank 67, the latter extending under the forked end 61 of the arm 55 to impinge against said arm, when the shaft 62 is rocked, to raise the arm 55 and open the damper 50.

Adjustable in the cold air draft flue 40, intermediate the ends thereof, is a gravity closing shutter or damper 68 having a weight 69 adapted to swing the damper to a vertical position to close the draft flue 40. The pintle 70 of the damper has an angular end or crank 71 normally engaging the cam member 66 of the rock shaft 62 and in consequence of this arrangement opening of the ash pit door 6 causes the damper 68 to be closed in advance of the damper 50 being opened.

The wall 15 of the combustion chamber 11, at the juncture of said wall with the flue connection 16, is provided with openings 72 and the front wall 5 is provided with openings 73 larger than the openings 72 but coaxial thereof. Connecting the walls 5 and 15 about the openings 72 and 73 are flared or tapering casings 74, and suitably mounted over the openings 73 are lens or transparent plates 75 which emit light from the lower ends of the flue connections 16 and permit of fire conditions being observed at the lower ends of the flue connections 16. The casings 74 serve somewhat as twyters permitting of the fire conditions within the furnace being observed and the furnace regulated or attended accordingly.

The furnace thus far described is intended for heating water circulated through the water jackets 19 and air circulated through the casing 25, but the principle of maintaining combustion in this furnace may be also utilized in the furnace employed as a source of heat for a water or steam circulating system. An example of such a furnace is shown in Fig. 2 where the combustion chamber 76 is surrounded by a water jacket 77 having lateral branches 78 communicating with another water jacket 79. The space between

the water jackets 77 and 79 constitutes up-flues 80 communicating with the lower end of the combustion chamber 76 and with an exhaust flue or T connection 81. It is in connection with this type of furnace that a plurality of superposed interchangeable units 82 may be employed to build up or increase the effective areas of the water jackets or flues, and in consequence of this unit construction a furnace may be provided to meet most any requirement of a heating apparatus.

Considering the operation of the furnace and assuming that the fire has been started 15 on the grate 10 and coal or other fuel placed in the magazine or combustion chamber, the cold air entering the flue 40 will pass downwardly through the down flue 38 and upwardly through the grate 10. Insomuch 20 that there is a bed of coal in the combustion chamber, preferably maintained at the height indicated by dot and dash lines in Fig. 3, the draft will not be through this bed of coal but outwardly at the sides of 25 the fire bed into the up flues 48 and to the atmosphere through the T connection 44. The down draft in the flue 38 moves gaseous products of combustion or non-inflammable gases from the upper portion of the 30 combustion chamber and delivers the same to the fire bed where the products of combustion will be consumed and the inflammable gases carried off by the upflues 48 to the atmosphere, therefore it makes no difference 35 if air passes upwardly through the coal in the combustion chamber for such air is returned, under normal operating conditions, to the fire bed. This means of circulating air through the fire bed means that 40 an intense fire is maintained at the lower ends of the flue connections 16 and may be observed through the twyters.

Coal may be readily placed in the magazine or combustion chamber without any 45 danger of gases exhausting at the opening 36 for the reason that the draft will be inwardly to the rear of the combustion chamber and downwardly through the flue 38.

If ashes are to be removed from the ash 50 pit, through the opening 4, opening of the door 6 closes the damper 68 shutting off the supply of air to the flue 38 and opening damper 50, which places the down flue 38 and the upper portion of the combustion chamber in communication with the atmosphere. Since the draft is 55 shut off from the down flue 38 ashes or gases will not be blown through the opening 4, but the draft will be induced inwardly 60 from the opening 4 upwardly through the grate flue 38 and combustion chamber and out of the opening 37 into the T connection 44 to the atmosphere. The lower part of the combustion chamber may also exhaust 65 to the atmosphere through the up flues 48.

By closing the damper 68 and opening the door 6 in synchronism and in advance of the damper 50 there is no danger of gases exhausting from the ash pit into the casing 70 25 or the cellar in which the furnace is located, and by having the damper 50 opened right after the damper 68 is closed there is no danger of gases being trapped in the furnace structure and causing an explosion 75 or leakage between parts of the furnace.

With the damper 50 operable independent of the damper 68 it is obvious that a draft can be produced from the flue 40 into the T connection, which draft will nullify to a certain extent the draft through the fire bed and thus retard the activity of the furnace for heating purposes.

While in the drawings there are illustrated the preferred embodiment of my invention, it is to be understood that the structural elements are susceptible to such variations and modifications as fall within the scope of the appended claims.

What I claim is:—

1. In a furnace wherein communicating up flues communicate with an outlet flue and the bottom of a combustion chamber at opposite sides thereof:—means for causing a uniform or equal draft in said up flues, said means being located where said up flues communicate with said outlet flue and causing a free draft flue to entrain smoke and gases from that flue in which a draft may be retarded into the outlet flue.

2. A furnace as called for in claim 1, wherein said means is in the form of a divisional partition extending in the direction of the outlet flue.

3. A furnace comprising a combustion chamber, a base piece supporting said combustion chamber, an up flue communicating with the bottom of said combustion chamber, a down flue connected to said base piece so that air may pass through said combustion chamber into said up flue, a T connection between said up and down flues communicating with the atmosphere and with said combustion chamber, and a damper in said T connection controlling the communication between said down flue and the atmosphere.

4. A furnace as called for in claim 3, and means operable at said base piece for adjusting said damper.

5. A furnace as called for in claim 3, and means operable through the top of said combustion chamber for adjusting said damper either from said base piece or remote from said furnace.

6. A furnace as called for in claim 3, and a draft flue extending into said down flue for producing a draft therein and removing gases from said combustion chamber.

7. A furnace comprising an ash pit, a combustion chamber, a down flue connected

to said ash pit and to the upper part of said combustion chamber, up flues connected to the lower part of said combustion chamber, a T connection between said up and down flues, a cold air draft flue communicating with said down flue, and means associated with said draft flue and said T connection to cause the combustion chamber to exhaust either direct or indirectly through said T connection.

8. A furnace as called for in claim 7 wherein said means includes dampers operable one in advance of the other.

9. A furnace comprising a combustion chamber adapted to have a fire therein, a down flue communicating with the combus-

tion chamber below the fire therein, and with the atmosphere independent of said combustion chamber, and means for causing said combustion chamber to exhaust into 20 said down flue and from said down flue either to the atmosphere or the lower part of said combustion chamber.

10. A furnace as called for in claim 9 wherein said means includes a damper at 25 the upper end of said down flue.

In testimony whereof I affix my signature in presence of two witnesses.

ALBERT A. BRUDER.

Witnesses:

ANNA M. DORR,
KARL H. BUTLER.
